3-ALKYLSULFONAMIDO-PYRIDINIUM SALTS

Mitchell F. Zienty, Elkhart, Ind., assignor to The Upjohn Company, Kalamazoo, Mich., a corporation of Michigan

No Drawing. Application January 28, 1948,
Serial No. 4,944

6 Claims. (Cl. 260—295)

1

This invention relates to quaternary ammonium compounds of certain N-substituted-3-pyridine sulfonamides.

The compounds of this invention are represented by the generic formula

Wherein R represents an alkyl radical having from 8 to 16 carbon atoms, inclusive, R' represents hydrogen or an alkyl radical having from 8 to 16 carbon atoms, inclusive, R'' represents a lower alkyl, lower alkenyl or aralkyl radical, and Z represents a halogen or an alkylsulfate radical (alkyl-SO4-). They may be designated conveniently as 3-N'-alkylsulfonamido pyridinium salts. It is understood that in the present application the symbol "N'" refers to the nitrogen atom of the amido radical.

The quaternary ammonium salts of the present invention are of value as wetting agents, surface tension depressants, detergents and, in particular, as germicides.

They can be prepared readily by warming a mixture of an N'-alkyl-3-pyridine sulfonamide and a hydrocarbon ester of an inorganic acid such as an alkyl halide, an alkenyl halide, an aralkyl halide or an alkyl sulfate to a reaction temperature.

The N'-alkyl-3-pyridine sulfonamide reactants used in preparing the quaternary compounds of the invention have the generic formula

wherein R and R' have the values given previously. These compounds include, among others, the following: N'-dodecyl-3-pyridine sulfonamide, N'-tetradecyl-3-pyridine sulfonamide, N'-hexadecyl-3-pyridine sulfonamide, N',N'-di-(2-ethyl-n-hexyl)-3-pyridine sulfonamide, N'-decyl-3-pyridine sulfonamide, N'-tridecyl-3-pyridine sulfonamide, N'-(2-ethyl-n-hexyl)-3-pyridine sulfonamide, N'-undecyl-3-pyridine sulfonamide, N',N'-di-dodecyl-3-pyridine sulfonamide, N',N'-di-decyl-3-pyridine sulfonamide, N',N'-di-undecyl-3-pyridine sulfonamide, N',N'-di-hexadecyl-3-pyridine sulfonamide, N'-hexadecyl-N'-undecyl-3-pyridine sulfonamide, N'-dodecyl-N'-

2

tetradecyl-3-pyridine sulfonamide, N'-dodecyl-N'-hexadecyl-3-pyridine sulfonamide, N'-decyl-N'-tridecyl-3-pyridine sulfonamide and N'-undecyl-N'-(2-ethyl-n-hexyl)-3-pyridine sulfonamide. The nature of the radicals R and R' in the quaternary compounds are determined by the N'-alkyl-3-pyridine sulfonamide used in any particular instance. Certain of the N'-alkyl-3-pyridine sulfonamides herein referred to are described and claimed in a con-currently filed, co-pending application Serial No. 4,943.

Lower alkyl and lower alkenyl radicals referred to herein, and represented by R'' in the first general formula given, are those containing less than 7 carbon atoms and include the methyl, ethyl, propyl, butyl, hexyl, ethenyl, propenyl, allyl, butenyl and pentenyl radicals. Aralkyl radicals represented by R'' in the general formula are those containing less than 12 carbon atoms and include the benzyl, phenylethyl, phenylpropyl, phenylbutyl, phenylisopropyl, tolylbutyl, tolyl-ethyl, xylylethyl and mesitylethyl radicals. Due to the ready availability of certain of their esters with inorganic acids, the preferred alkenyl and aralkyl radicals are the allyl and benzyl radicals, respectively. Non-cyclic radicals referred to herein, and represented by R, R' or R'', can be either straight or branched chain. Hydrocarbon esters of inorganic acids which can be used in forming the quaternary ammonium compounds include methyl iodide, ethyl chloride, n-butyl bromide, isobutyl bromide, hexyl iodide, allyl bromide, propenyl bromide, butenyl chloride, dimethyl sulfate, diethyl sulfate, benzyl chloride, p-tolylolethyl chloride, and many others.

The reaction can be carried out in the presence of an inert liquid diluent, such as an alcohol or a hydrocarbon, or without the use of a diluent, as desired, and at any suitable temperature below the decomposition temperature of the reactants or product. Good yields of product have been obtained by heating the mixture to between about 50° and about 150° C. One of the reactants, or a solution thereof in an inert diluent, can be added portionwise and with mixing to the other reactant at the reaction temperature, if desired, although this is not necessary.

Any suitable proportions of reactants can be employed, any excess of either of the reactants being removed from the quaternary ammonium compound during the isolation and purification steps. In practice, it has been found desirable to use either equimolecular proportions of the reactants or to employ a substantial excess of the hydrocarbon inorganic ester. Such excess ap-

pears to serve as a solvent for the reactants which favors the reaction and does not materially complicate isolation of the quaternary ammonium compound. Usually not more than 1.5 molecular proportion of hydrocarbon inorganic ester is employed. The reaction is usually substantially complete in from a few minutes to several hours.

The reacted mixture is cooled to about room temperature, or below, to crystallize the quaternary ammonium salt, which is obtained as a 10 white, yellow or tan solid. When a diluent is used in which the reaction product is soluble, isolation is best accomplished by removal of the diluent, preferably under reduced pressure. The crude product thus obtained can be employed without further modification as a constituent of germicidal, wetting or surface tension depressant compositions or it can be purified further, e. g. by crystallization. Such crystallization is conveniently accomplished by dissolving the crude salt in a small amount of a hot inert solvent, such as ethyl acetate or an acetone-hexane mixture or a mixture of petroleum ether and ethyl ether, cooling the solution, separating the precipitated crystals by decantation or filtration and drying the crystals thus obtained.

The following examples serve to illustrate the invention but are not to be construed as limiting.

EXAMPLE 1

To a solution of 3-pyridine-sulfonyl chloride, prepared from 10 grams of 3-pyridine-sulfonyl chloride, in 50 milliliters of dry benzene cooled at about 10° C., there was added a cooled solution of 30 grams of hexadecyl amine in 100 milliliters of dry benzene. A precipitate of hexadecyl amine hydrochloride which formed was removed by filtration. The filtrate was evaporated to dryness, and the solid residue crystallized from a mixture of benzene and petroleum ether (B. P. 90°-100° C.). Fifteen grams of N'-hexadecyl-3-pyridine sulfonamide was obtained melting at 78°-79° C.

Other N'-alkyl-3-pyridine sulfonamides were prepared in a similar manner.

EXAMPLE 2

A solution of 1.25 grams of N'-hexadecyl-3-

pyridine sulfonamide and 0.6 gram of methyl iodide in 15 milliliters of absolute ethanol was refluxed for six hours. The alcohol was evaporated and the yellow residue dissolved in warm 5 ethyl acetate. Upon cooling the solution a precipitate formed which was recovered by filtering and drying. There was thus obtained 1.5 grams of 3-N'-hexadecylsulfonamido-1-methyl pyridinium iodide melting at 165°-166° C.

EXAMPLE 3

A mixture of 1.5 grams of N'-hexadecyl-3-pyridinesulfonamide and 0.49 gram of benzyl chloride was heated at 110° C. for two hours. 15 The crystalline mass which formed when the mass cooled was crystallized from ethyl acetate. There was thus obtained 1.8 grams of 3-N'-hexadecylsulfonamido-1-benzyl pyridinium chloride melting at 160°-161° C.

EXAMPLE 4

A mixture of two grams of N'-hexadecyl-3-pyridine sulfonamide and 0.75 gram of dimethyl sulfate was heated at 100° C. for three hours. 25 The unreacted dimethyl sulfate was removed by washing with petroleum ether. The semi-solid 3-N'-hexadecylsulfonamido-1-methyl pyridinium methosulfate obtained was purified by recrystallization from ethyl acetate. The colorless plates obtained weighed 2.1 grams and melted at 30 104°-105° C.

EXAMPLE 5

A number of 4-N'-alkylsulfonamido pyridinium salts were prepared substantially as by 35 the procedures given in Examples 2, 3 and 4. The melting points of the compounds were determined and they were each analyzed quantitatively for halogen or nitrogen. The germicidal effectiveness of each of the compounds was determined by the method of Ruehle and Brewer (U. S. D. A. Circular; 198 4 (1931)). The data obtained is given in the accompanying table and the results expressed in terms of the greatest dilution of the pure individual compound which 45 will kill *Staphylococcus aureus* in 10 minutes but not in 5 minutes at 37.5° C. Data on the compounds prepared in Examples 2, 3 and 4 are included in the table.

Table

3-N'-alkylsulfonamido pyridinium salts having the generic formula:

^a-2-Ethyl-n-hexyl.
^b-Nitrogen, percent.

I claim:

1. A compound having the general formula

wherein R is a member of the group consisting of the alkyl radicals containing from 8 to 16 carbons, inclusive, R' is a member of the group consisting of hydrogen and the alkyl radicals containing from 8 to 16 carbon atoms, inclusive, R'' is a member of the group consisting of the lower alkyl, lower alkenyl and aralkyl radicals, and Z is a member of the group consisting of the alkylsulfate and halogen radicals.

2. A compound as claimed in claim 1 wherein R' represents hydrogen.

3. 3-N',N'-di-(2 - ethyl-n-hexyl) -sulfonamido-1-methyl-pyridinium iodide.

4. 3-N' - dodecylsulfonamido-1-benzyl-pyridinium chloride.

5. 3-N'-hexadecylsulfonamido-1-allyl-pyridinium bromide.

6. The method which includes: heating a compound having the formula

5

wherein R represents a member of the group consisting of the alkyl radicals containing from 8 to 16 carbon atoms, inclusive, and R' represents a member of the group consisting of hydrogen and the alkyl radicals containing from 8 to 16 carbon atoms, inclusive, with a compound from the group consisting of the lower alkyl, lower alkenyl and aralkyl halides and sulfates; and separating from the reaction mixture a compound having the formula

20

15

wherein R'' represents a member of the group consisting of the lower alkyl, lower alkenyl and aralkyl radicals and Z represents a member of the group consisting of the alkylsulfate and halogen radicals, R and R' having the values given.
